UNITED STATES PATENT OFFICE

150,533

DESIGN FOR A SHORT DRESS BELT

Lee Roy Baggett, Hot Springs, Ark.

Application April 18, 1947, Serial No. 138,486

Term of patent 14 years

(Cl. D3—10)

To all whom it may concern:

Be it known that I, Lee Roy Baggett, a citizen of the United States, residing at Hot Springs, in the county of Garland and State of Arkansas, have invented a new, original, and ornamental Design for a Short Dress Belt, of which the following is a specification, reference being had to the accompanying drawings, forming a part hereof.

I claim:

The ornamental design for a short dress belt, as shown.

LEE ROY BAGGETT,
